DESIGN FOR CHESS PIECES

Shepard J. Goldin, New York, N. Y.

Application January 5, 1940, Serial No. 89,308

Term of patent 14 years

To all whom it may concern:

Be it known that I, Shepard J. Goldin, a citizen of the United States of America and residing at New York, in the county of New York and State of New York, have invented a new, original, and ornamental Design for Chess Pieces, of which the following is a specification, reference being had to the accompanying drawing, forming part thereof, and in which:

Fig. 1 shows face views of the chess pieces embodying my new design; and

Fig. 2 is a sectional view taken on line 2—2 of one of the chess pieces disclosed by Fig. 1.

I claim:

The ornamental design for chess pieces, substantially as shown.

SHEPARD J. GOLDIN.
